ANALYZER OF ORGANIC MATERIAL CONTENT IN SEWAGE WATER OR THE LIKE

Kurt H. Nelson, Thousand Oaks, and Lawrence H. Groeper, Woodland Hills, Calif., assignors to North American Rockwell Corporation

Filed Dec. 30, 1968, Ser. No. 15,187

Term of patent 14 years

Int. Cl. D10—11; D24—02

U.S. Cl. D16—2

FIG. 1

FIG. 2

FIG. 5

FIG. 3

FIG. 6

FIG. 4

FIG. 1 is a perspective view of an analyzer of organic material content in sewage water showing our new design;

FIG. 2 is a front plan view;

FIG. 3 is a top plan view;

FIG. 4 is a bottom plan view;

FIG. 5 is a back plan view; and

FIG. 6 is an end view.

We claim:

The ornamental design for an analyzer of organic material content in sewage water or the like, as shown.
